CHARLES C. BLAKEMORE, OF WASHINGTON COURT-HOUSE, ASSIGNOR TO GEORGE C. ROBINSON AND HENRY A. MANNING, OF CINCINNATI, OHIO.

Letters Patent No. 79,194, dated June 28, 1868.

IMPROVEMENT IN CARD OR TICKET-CASES.

The Schedule referred to in these Letters Patent and making part of the same.

TO ALL WHOM IT MAY CONCERN:

Be it known that I, CHARLES C. BLAKEMORE, of Washington Court-House, Fayette county, State of Ohio, have invented a certain new and useful Card-Case or Ticket-Holder; and I do hereby declare the following to be a full, clear, and exact description thereof, reference being had to the accompanying drawings, making part of this specification.

My invention consists in a peculiar construction of case and cover, and the provision, within the case, of devices which enable the holder to push out the cards (by a mere pressure of a thumb or finger) one at a time. In the accompanying drawings—

Figure 1 is a perspective view of the case or holder open and empty.

Figure 2 is a cross-section when the case is filled with tickets or cards, and closed.

Figure 3 is a view exhibiting the same in use.

The case or holder may be of any desired size to hold business or visiting-cards or car-tickets, and it is composed of the following parts; to wit, a shell or case, A, constructed to hold elastic lips B at the ends, a hinged cover or lid C, and a rectangular wire spring, D.

The lid or cover C is hinged to the case A at a, and has a hole cut through it sufficiently large to enable the fingers of the operator to push out the cards from the end of the case. The sides of the cover are perforated at b to engage over the catches a' of the case, so as to hold the cover when it is closed.

The spring D, when the case is filled and closed, serves to keep the pack pressed against the cover of the case. The cards or tickets can then be forced out in the manner exhibited in fig. 3, one at a time only, until the pack is entirely gone. The lips B close up the ends of the case when the cover is down, and only give way when a card is pressed out at either end by the fingers of the operator. The lip against which the card presses, then yields sufficiently to let the card pass.

I claim herein as new, and of my invention—

The case A, hinged open-face cover C, rectangular spring D, and elastic lips B, combined, arranged, and operating in the manner and for the purpose specified.

In testimony of which invention, I hereunto set my hand.

Witnesses:

GEO. H. KNIGHT,

JAMES H. LAYMAN.

CHARLES C. BLAKEMORE.
